UNITED STATES PATENT OFFICE

172,052

AUTOMOBILE WHEEL DISK

Ned F. Nickles, Detroit, Mich., assignor to General Motors Corporation, Detroit, Mich., a corporation of Delaware

Application February 9, 1953, Serial No. 23,520

Term of patent 7 years

(Cl. D14—30)

To all whom it may concern:

Be it known that I, Ned F. Nickles, a citizen of the United States, being a resident of Detroit, Michigan, have invented a new, original, and ornamental Design for an Automobile Wheel Disk, of which the following is a specification, reference being made to the accompanying drawing, forming a part thereof.

In the drawing:

Figure 1 is a front elevational view of an automobile wheel disk incorporating my new Design;

Figure 2 is a side elevational view thereof;

Figure 3 is a sectional view on the line 3—3 of Figure 1.

The dominant features of my design reside in the portions shown in full lines.

I claim:

The ornamental design for an automobile wheel disk, substantially as shown and described.
